Primary Examiner — David Muller(74) *Attorney, Agent, or Firm* — Lowe Hauptman & Ham, LLP(57) **CLAIM**

The ornamental design for a pedicure spa base, as shown and described.

DESCRIPTION

FIG. 1 is a perspective view of the pedicure spa base;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof.

The broken lines of FIG. 8 form no part of the claimed design and are used to illustrate environmental structure.
